NECKTIE RACK

Cyril Kruger, New York, N. Y.

Application February 16, 1955, Serial No. 488,464

1 Claim. (Cl. 211—104)

This invention relates to new and useful improvements in tie racks for hanging neckties, cravats and the like in spaced relation.

More particularly, the present invention proposes the construction of an improved tie rack having a plurality of tie holding arms which can be folded substantially flat in either direction or positioned at various angles for hanging neckties thereon.

As a further object, the present invention proposes forming the tie rack with two spaced bars having a number of tie holding members pivotally connecting the bars and all having vertical shank portions and horizontal portions disposed in single vertical plane for each tie holding member.

Still further, the present invention proposes constructing the tie rack with parts easy and simple to operate and inexpensive to manufacture.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a perspective view of a tie rack constructed and arranged in accordance with the present invention.

Fig. 2 is a sectional view taken on line 2—2 of Fig. 1.

Fig. 3 is an enlarged sectional view taken on line 3—3 of Fig. 1.

Fig. 4 is a fragmentary top plan view of the structure shown in Fig. 2.

Fig. 5 is a fragmentary top plan view of the structure shown in Fig. 3.

Fig. 6 is a view similar to Fig. 1 but illustrating a modification of the present invention.

Fig. 7 is a sectional view taken on line 7—7 of Fig. 6.

Fig. 8 is a view similar to Figs. 1 and 6 but illustrating another modification of the present invention.

Fig. 9 is a sectional view taken on line 9—9 of Fig. 8.

The tie rack, in accordance with the first form of the invention illustrated in Figs. 1 to 5, inclusive, is designated generally by the reference numeral 15.

Tie rack 15 has two spaced parallel bars 16 and 17 made of wood, plastic, glass, metal or other such material. Bar 16 is the top bar and bar 17 the bottom bar of the tie rack. Top bar 16 has upper and lower edges 18 and 19 and front and rear faces 20 and 21 respectively. Bottom bar 17 likewise has upper and lower edges 22 and 23 and front and rear faces 24 and 25 respectively.

A plurality of tie holding rod members 26 pivotally connect the two bars 16 and 17. The tie holding rod members 26 each are one continuous rod bent or otherwise formed so as to have vertical shank portions 27 and 28 and horizontal tie holding arms 29 and 30. All of the shank portions (27 and 28) and all of the arms (29 and 30) of each rod member 26 are disposed in the same vertical plane so that there are no twisted or offset portions.

Shank portion 27 of each rod member 26 pivotally ex-

2

tends through the lower or bottom bar 17 of the tie rack depthwise of the bar, this bar 17 being provided with a plurality of spaced holes or openings 31 to permit this. The other shank portion (shank portion 28) of each rod member 26 is pivotally connected with the other bar 16. These shank portions 28 extend into the lower edge 18 of the top bar 16 of the rack, this lower edge 18 being provided with a plurality of spaced holes or openings 32 pivotally to receive these shank portions 28.

In addition to the tie holding rod members 26, two end tie holding rod members 33 and 34 are provided at the two ends of the tie rack. These end tie holding rod members 33 and 34 have vertical shank portions 35 and horizontal portions 36 and 37 all disposed in the same vertical plane. The shank portion 35 of each end tie holding rod member pivotally extends through the lower or bottom bar 19 depthwise of the bar and extends behind the rear face 21 of the top bar 16. The bottom bar 19 is provided with holes or openings 38 and 39 spaced from its ends 40 and 41, respectively, pivotally to pass the shank portion 35 of end tie holding rod members 33 and 34, respectively.

Horizontal portion 37 of each end tie holding rod member is a connecting arm extending toward the top bar 16 partially across the upper edge 18 of the top bar. The horizontal portion 37 of each end tie holding rod member has a vertical portion 42 pivotally extending through the upper edge 18 of the top bar 16, openings 43 and 44 being provided for this.

Horizontal portion 36 of each end tie holding rod member is a tie-holding arm having an upwardly inclined free end portion 45. Preferably the end tie holding rod members 33 and 34 are identically constructed each of a single rod bent or otherwise formed with the horizontal and vertical and inclined portions described all in the same vertical plane with no twisted or offset portions.

The horizontal tie holding arm 29 on each of the plurality of tie-holding rod members 26 is a single arm with a free end portion 46 which is upwardly inclined and the arm 30 on each of these members 26 is a double arm with an upwardly inclined end portion 47.

Lower or bottom bar 17 is provided with spaced screw holes or openings 48 and 49 for mounting the tie rack on a wall, door or other surface.

It is to be noted that the length of the upper portion 30' of the doubled tie holding arm 30 is shorter than that of the lower arm 30" forming in effect a crank.

In operation, the tie rack 15 can be folded substantially flat with the tie-holding rod members all pivoted in either pivoting direction, to the left or to the right. Likewise, the tie-holding rod members may be pivoted to any intermediate position for receiving ties in such position or positions.

The modification of the invention illustrated in Figs. 6 and 7 is characterized by the provision of a tie rack 50 having spaced parallel bars 51 and 52, bar 51 being the top bar and bar 52 the lower or bottom bar. Top bar 51 has upper and lower edges 53 and 54 and front and rear faces 55 and 56. Bottom bar 52 has upper and lower edges 57 and 58 and front and rear faces 59 and 60.

A plurality of spaced tie-holding rod members 61 pivotally connect the two bars 51 and 52. The tie-holding rod members 61 are all alike and are each one continuous rod bent or otherwise formed so as to have vertical shank portions 62 and 63 and three horizontal tie-holding arms 64, 65 and 66. The arms 64 and 66 are single arms with free end portions 67 and 68 which are upwardly inclined while the central arm 65 is a double arm having an upwardly inclined end portion 69. All the shank portions (62 and 63) and all the horizontal tie-holding arms (64, 65 and 66) are in the same vertical plane with no twisted or offset portions. Double arm

65 has an upper portion 65' which is shorter in length than the lower portion 65" thus forming in effect a crank.

The bottom bar 52 is provided with spaced screw holes or openings 70 and 71 for mounting the tie rack and bottom and top bars 52 and 51 are provided with spaced openings 72 and 73 pivotally to pass the shank portions 63 and 62, respectively, of each tie-holding rod member 61.

The modification of the invention illustrated in Figs. 8 and 9 is characterized by the provision of a tie rack 80 having an upper or top bar 81 and a lower or bottom bar 82. Top bar 81 has upper and lower edges 83 and 84 and bottom bar 82 has upper and lower edges 85 and 86. Bottom bar 82 is provided with spaced screw holes or openings 87 and 88 for mounting the tie rack.

A plurality of tie-holding rod members 89 are provided pivotally connecting the bars 81 and 82 together. These members 89 are each one continuous rod bent or otherwise formed so as to have vertical shank portions 90 and 91 and horizontal tie-holding arms 92 and 93. The arm 92 of each member 89 is a single arm with an upwardly inclined free end portion 94 and the arm 93 of each member 89 is a double arm with an upwardly inclined end portion 95. The double arm 93 has an upper portion 93' which is shorter than the lower portion 93" to give a crank effect.

Bottom bar 82 is provided with spaced holes or openings 96 and the shank portions 90 of the rod members 89 pivotally extend through these openings 96. Likewise, the lower edge 84 of the top bar 81 is provided with spaced holes or openings 97 pivotally to receive the shank portions 91 of the rod members 89.

In addition to the rod members 89, two end tie-holding rod members 98 and 99 are provided. These end tie-holding members are constructed similar to rod members 89 but have vertical shank portions 100 and 101, the shank portions 101 being longer than shank portions 91 of the rod members 89. The end tie-holding members 98 and 99 also have horizontal tie-holding arms 102 and 103 constructed identical to arms 92 and 93 on the rod members 89.

Bottom bar 82 is also provided with openings 104 and 105 pivotally to hold the shank portions 100 of the end tie-holding rod members 98 and 99. Top bar 81 has similar holes or openings 106 and 107 pivotally to hold 45

the shank portions 101 of the end tie-holding rod members 98 and 99. Spherical balls 108 and 109 are provided on the ends of the shank portions 101 of the end tie-holding rod members 98 and 99 to form turning and locking members disposed adjacent the upper edge of the top bar 81 by means of which all the tie holding arms may be pivoted.

While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent is:

A tie rack comprising two spaced upper and lower bars and a plurality of tie-holding rod members pivotally connecting and interlocking the bars, said rod members each having vertical shank portions and three horizontal tie-holding arms extending partially across the top and bottom edges of the bars, said arms and shank portions of each rod member being disposed in the same vertical plane, one of the arms of each rod member being a lower tie-holding arm, another of the arms being an intermediate doubled tie-holding arm and the third arm being a single upper tie-holding arm, and one of the shank portions of each rod member pivotally extending through one of the bars depthwise of the bar and another shank portion of each rod member pivotally extending through the other bar depthwise of the bar, the upper bar being spaced forwardly of the lower bar.
